UNITED STATES PATENT OFFICE.

JAMES WILKINSON, OF BOSTON, MASSACHUSETTS, ASSIGNOR TO GENERAL ELECTRIC COMPANY, A CORPORATION OF NEW YORK.

NOZZLE-PLUG FOR FLOW-METERS.

1,110,023.

Specification of Letters Patent.

Patented Sept. 8, 1914.

Application filed June 5, 1912. Serial No. 701,888.

To all whom it may concern:

Be it known that I, JAMES WILKINSON, a citizen of the United States, residing at Boston, in the county of Suffolk, State of Massachusetts, have invented certain new and useful Improvements in Nozzle-Plugs for Flow-Meters, of which the following is a specification.

This invention relates to nozzle plugs for fluid flow meters which operate on the general principle of a Pitot tube.

The object of my invention is to provide a plug of this type constructed in such a manner that its cost of manufacture is greatly decreased and its operation improved.

Briefly stated, my improved plug consists of a stout pin, adapted to be inserted into the main through which the fluid to be metered is flowing, and provided on opposite sides with longitudinal grooves connected respectively with tubes which extend to the mercury cups or similar devices of the meter.

In the accompanying drawing, Figure 1 is a longitudinal section of a nozzle plug embodying one form of my invention; Fig. 2 is a side view of said plug; Fig. 3 is a cross section taken on the line 3-3, Fig. 2; Fig. 4 is a longitudinal section of the plug as used in a vertical main; and Fig. 5 is a cross section of a modification.

The main 1 through which the fluid to be metered flows in the direction of the arrow is arranged horizontally in Figs. 1 and 2 and vertically in Fig. 4. The fluid may be steam, air, water or other fluid. The main is tapped at some convenient point to receive the screw-threaded base 2 of the nozzle plug which has a polygonal collar 3 outside of said screw-threaded portion to receive a wrench. Projecting into the main from said base is a stout pin 4 which is preferably long enough to extend substantially across the main in a diametrical direction. In order to obtain the requisite strength for the pin, I form the same of greatest cross-sectional area at its base where the greatest strain comes and gradually decrease its cross-section from the base toward the outer end. Since any such device offers a certain limited obstruction to the passage of the fluid, I prefer to make the pin as thin in cross section as possible, measured in a direction transverse of the

main; but in a longitudinal direction of said main the pin is considerably thicker, so as to obtain the requisite strength, it being noted that said pin is supported at one end only although a support for the other end can be provided if desired. In opposite faces of the pin are formed longitudinal grooves 5, 6 the former facing the moving column of fluid and the latter facing in the opposite direction. For convenience, the groove 5 may be called the leading groove and the 6 other the trailing groove. In order to obtain the average effect of the fluid velocity the grooves should extend substantially the entire length of the pin and said pin should be long enough to extend substantially 70 across the main; but good results can be secured with a shorter pin, if necessary. At the end adjacent to the base 2 each groove communicates with a passage 7 in said base, and said passages connect respectively with 75 the tubes 8 that lead to the meter. The grooves may be arranged in the same plane, as shown in Fig. 3; or, if desired, they may be arranged in different planes, slightly oblique to the longer diameter of the 80 pin, as shown in Fig. 5; the latter construction permitting deeper grooves to be used. When the plug is inserted in a vertical main, I prefer to drill a small hole 9 connecting the two grooves near the outer end of the pin 85 to drain off any water of condensation that may collect in the upper groove.

Ordinarily, these nozzle plugs are provided with circumferential fins integral with the base to dissipate the heat of the fluid 90 flowing into the tubes 7. I prefer to make these fins as separate disks 10 provided with tapped holes through which the upper ends 95 of the tubes 8 are screwed, the disks being spaced apart to give the requisite air channels between them. A nozzle plug constructed in this manner is simple and efficient, and is much less costly to make than those with which I am familiar.

In accordance with the provisions of the 100 patent statutes, I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is,—

1. A nozzle plug for flow meters comprising a screw threaded base that is adapted to be threaded into an opening in the main carrying the fluid to be metered, and a long narrow pin extending from said base which has narrow grooves extending from end to end, said grooves facing in opposite directions and separated by a partition, the base being provided with conduits extending therethrough connecting respectively with the grooves.

2. A nozzle plug for flow meters comprising a screw threaded base that is adapted to be threaded into an opening in the main carrying the fluid to be metered, and a long narrow pin that is formed integral with the base and gradually decreases in cross-section from the base toward its outer end and has narrow grooves on opposite sides which extend from end to end of the pin and are separated from each other by a partition forming an integral part of the plug, the base being provided with independent conduits that communicate respectively with said grooves.

3. A nozzle plug for flow meters comprising a screw threaded base that is adapted to be threaded into an opening in the main carrying the fluid to be metered, and a long narrow pin that is formed integral with the base and gradually decreases in cross-section

from the base toward its outer end, said pin having a greater dimension in the direction of flow of the fluid than in a direction perpendicular thereto and provided with oppositely facing narrow grooves extending longitudinally thereof and separated at their adjacent sides by a partition forming an integral part of the pin, the base being provided with independent conduits that extend therethrough into the pin and communicate with the said grooves.

4. A nozzle plug for flow meters, comprising a screw threaded base that is adapted to be threaded into an opening in the main carrying the fluid to be metered, and a long narrow pin that is formed integral with the base and provided with narrow grooves on opposite sides extending longitudinally thereof and which are separated from each other on their adjacent sides by a partition forming an integral part of the plug, said partition being provided with a small opening connecting the grooves near their outer ends, the base being provided with independent conduits extending therethrough and communicating with the grooves for conveying fluid to a meter.

In witness whereof, I have hereunto set my hand this first day of June, 1912.

JAMES WILKINSON.
